[57] CLAIM

The ornamental design for an electrosurgical current suppressor, as shown and described.

DESCRIPTION

FIG. 1 is a front perspective of an electrosurgical current suppressor, showing our new design;

FIG. 2 is a rear perspective of the suppressor;

FIG. 3 is a top plan view;

FIG. 4 is a front elevation of the suppressor;

FIG. 5 is a side elevation from the right of FIG. 1;

FIG. 6 is a bottom plan view;

FIG. 7 is a rear elevation of the suppressor;

FIG. 8 is a side elevation from the left of FIG. 2;

FIG. 9 is a front perspective of a modified form of the suppressor;

FIG. 10 is a rear perspective of the modified suppressor;

FIG. 11 is a top plan view of the modified suppressor;

FIG. 12 is a front elevation of the modified suppressor;

FIG. 13 is a side elevation from the right of FIG. 9;

FIG. 14 is a bottom plan view of the modified suppressor;

FIG. 15 is a rear elevation of the modified suppressor;

and

FIG. 16 is a side elevation from the left of FIG. 10.
